UNITED STATES PATENT OFFICE

ANALDO M. ENGLISH, OF BROOKLINE, MASSACHUSETTS, ASSIGNOR TO CYNTHIA MILLS
OF EAST BOSTON, MASSACHUSETTS, A CORPORATION OF MASSACHUSETTS

BAND FEEDER

Application filed February 7, 1928. Serial No. 252,452.

This invention relates to package banding machines for the purpose of wrapping or banding a package or skein of embroidery yarn, tape, braid, fish line or the like (or other small articles of various sorts) and broadly considered contemplates means for applying a flexible band or wrapper about a package and securely attaching the same in place, for example, by means of an adhesive.

The principal objects of the invention are to provide a machine adapted to wrap and affix a suitable band or label about a package neatly, efficiently, and uniformly as hereinafter described, and eliminate to a large extent the labor and expense of wrapping by hand. Other objects and advantages will hereinafter appear.

In the drawings:

Fig. 1 is a perspective view of the complete machine looking towards it from the front and one side of the same;

Fig. 2 is a side elevation illustrating the band or label handling device in one position preparatory to taking a band from a reservoir or supply of the same;

Figs. 3, 4 and 5 are additional views showing successive positions of the same device;

Fig. 6 is a view in side elevation showing the band handling device associated with other parts of the machine;

Figs. 7, 8 and 9 are side elevations, partly in section, illustrating steps in the wrapping of a band about a package;

Fig. 10 is a perspective view, slightly enlarged, showing a portion of the band handling device including the band reservoir, pricker, and band pincers;

Fig. 11 is an enlarged perspective view showing the band pincers; and

Fig. 12 is a perspective view, somewhat enlarged, showing the steps which control the opening and closing of the band pincers shown in Fig. 11.

The machine shown in the drawings is, in many of its essentials, the same in construction as that shown in my pending application, Serial No. 122,811, filed July 16, 1926, and reference is made to the disclosure of that application.

Referring to the drawings herein (Figs. 1,

6-9), 2 designates an oblong shaped member comprising a rocking or swinging frame of an initial seizing or holding assembly, 4 the shaft upon which the same is fastened for operation when said shaft is rocked by means (not shown) suitably timed with the other parts hereinafter described, so as to operate substantially in accordance with the disclosure of the above mentioned application. Pivoted to the member 2 are seizing means 55 including seizers 14. The seizers are levers so pivoted to and carried by the member 2 that when the same is swung towards the operator seated at the front of the machine, the lower ends of the seizers 14 come in contact with the members 18 slidably held and actuated (by suitable means not shown, though they may be adjusted and left in a fixed position) in a portion of the water box supporting frame 15 so that the upper ends 60 of the seizers 14 open and swing away from the member 2. Thus the seizers together form one jaw of the initial holding assembly and the upper transverse portion of the member 2 forms the opposite jaw of the initial holding or seizing assembly, which hereinafter 65 may be referred to as assembly A. The seizers 14 normally tend to close or grip because of the springs 20. In Fig. 6 a package designated at p and a band designated at b are 70 shown placed in position between the jaws of the assembly A which engage or seize the package as the members 18 are retracted against the pressure of the springs so that the springs 20 can rock the seizers 14 and cause them to engage the package p and band b. In Fig. 6 the lower edge of the band or label b is shown as being placed upon an adjustable rest 22 which fixes its position with 75 reference to assembly A and with reference to the package which is placed between the jaws of the seizing assembly and rests in the notched upper ends of the seizers 14 and outside of the end seizers. Referring again to Fig. 6, at the left a package is shown, together with one of the labels, between the jaws of assembly A with the same swung away from the receiver and in open position over the water-box, moistening rolls and adjustable label rest 22, as clearly shown in Fig. 6. The 80

space between the upright sides of the swinging member 2 and assembly A is sufficiently wide to clear the sides of a moistening device, as here shown, comprising a water-box 5 17 and moistening rolls 19, which are suitably held in pivoted arms 23 (and in which they are free to rotate) so that the lower roll, at least, is always partially immersed in the water, the lower moistening roll 19 contacting 10 with the upper roll 19 across the band *b* is wiped (and also slightly rotating the same) as the seizing assembly swings away from its forward position and under the receiver. The spring 24 bearing on the lower arms 23 holds up the lower roll 19 so that it contacts 15 with and bears the weight of the upper roll 19. The gummed portion of the label *b* is designated at *g*, see Fig. 6 at the left, whereas the lower portion of the opposite side of 20 the band *b* contacts with the upper moistening roll 19 as assembly A swings toward the left. The seizing means is provided with arms 12^a which contact with the member 26 and lift the center seizer away from the package and its band *b* just before the end of the 25 swing of assembly A where it dwells pending the removal of the package and band so that the rams 28 and 30 have a free passage in their upward movement between the end 30 seizers whereby the package and band are removed from the grasp and the end seizers by the rams and are forced into and between the wing 32 and the spring pressed clip 34 of the rotating receiver generally designated 35 at 36. The ram 28 is loosely jointed to the lever 38, and the ram 30 is pivoted to the lever 40, the ram 30 being the driving member and the ram 28 being the driven member on both the up and down strokes of the rams. 40 The two rams are held together in parallel relation by means of bolt 31 which slides in the opening 30^a of the ram 30, and passes through a hole in ram 28 in which the bolt 31 is held. The ram 30 is driven through 45 its arm 40 by the rock shaft 50 and thereby moves the ram 28 up and down, the up and down movement of the latter, however, being delayed by means of the friction plates 52 which engage the opposite sides of the enlargement upon the fulcrumed end of the arm 38 so that the ram 28 is only moved as the screw 31 engages the ends of the slot 30^a. It will be seen from Fig. 1 that the arm 38 is journaled on shaft 39 between the plates 53 52 which, though fixed to prevent their rotation, are adjustable towards each other by means of the nut 54 holding them together so as to cause a suitable drag or friction upon the arm 38 which tends to retard the movement of the ram 28 in the upward and downward movements of the ram 30, the purpose 60 of which will presently appear. The rock shaft 50 is suitably actuated and timed by suitable means (not shown).

The rams 28 and 30 are shown in Fig. 6 at

their lower position, free and clear of the rotating receiver 36 which is turned a step at a time between each up-stroke of the ram by means (not shown) such as disclosed in my pending application, which imparts a step-by-step rotation to the receiver. When the ram 30 starts up, it first advances beyond the end of the ram 28 as from the position shown in Fig. 6 to that shown in Fig. 7, the arms 12^a by reason of their contact with the member 26 having lifted the center seizer 12 so that the package is free along its central portion (see Fig. 6). This allows the ram 30 to pass upwardly and bend the lower edge of the label *b* upwardly and about the package, as clearly shown in Fig. 7. At the same time as the package and label are forced upwardly into a recess the clip 34 completes the bending of the upper and gummed edge of the label downwardly and outside of the ram 30 (Figs. 8 and 9), the initial bending of the upper edge of the label *b* about the package having been caused by the contact of the lower end of the clip 34 with the upper edge of the label near the completion of the backward swing of assembly A (see Fig. 6). The upper end of the ram 30 is shown in Fig. 8 as interposed between the moistened portion of the label and its gummed surface. As the ram 30 continues its upward movement, its beveled surface engages and gradually lifts the end seizers 14 and thus finally releases their grasp upon the package and label just after the rams have engaged the package and label and have started to carry them upwards. They are then forced into the space or opening between the wings 32 and the spring-pressed clips 34. As the ram 30 continues upward from the position shown in Fig. 7 to the position shown in Fig. 8, the ram 28 is also carried upward and bears upon the lower portion of the label and package forcing the same upwardly and still further into the opening in the resilient receiving pocket. Fig. 8 shows the rams at the moment their upward stroke has been completed, and with the ram 30 still interposed between the overlap of the label *b*. Fig. 9 shows the rams just after the ram 30 has completed that portion of its downward stroke which takes place while the ram 28 is at rest (because of the friction plates which tend to hold the ram 28 in any position unless actuated by the bolt 31 in the slot 30^a of the ram 30). This action allows the ram 30 to be partially retracted without lowering or otherwise disturbing the package, which continues to be held by the ram 28, and as the ram 30 is retracted, the spring-pressed clip 34 forces the dry gummed surface of the wrapper or label against the opposite moistened surface thereby effecting an attachment between the two as the ram 30 passes out from between the two surfaces of the label.

The ram itself never comes in contact with sticky gum for the dry gum first comes in contact with the moistened wrapper behind the retreating beveled edge of the ram 30. It will be plain from Fig. 9 that the ram 30 in the balance of its downward movement carries with it the ram 28 until the two rams are below and clear of the wings 32 of the receiver 36 so that it will again be free to be rotated another step.

The packages continue around in the course of the rotation of the receiver 36 being held and pressed a sufficient interval during the rotation of the receiver so that the moistened and gummed surfaces of the labels sufficiently dry to effect a permanent attachment of the same before being discharged from the receiver. As the wings of the receiver successively near their lowermost position the arm 62 with its finger and guide 63 is pressed upwardly and against each clip of the receiver as it reaches this position so that the wrapped packages are released and drop downwardly and out of the receiver as each clip is lifted.

The package feeding mechanism shown in the accompanying drawings (Figs. 1 and 6) includes a revolving reel 41 made up of two disk-like side member spaced from one another and having notches 42 in their peripheries so shaped as to be adapted to hold the packages or skeins placed therein and feed the same to assembly A, when it dwells at the forward end of its swing. Fig. 1 shows the feed reel with the available notches as having been filled by the operator and as about to deliver or deposit a package in the jaws of assembly A. The feed reel 41 is affixed to and revolved by the shaft 43 which is rotated by means of a driven pulley and belt (not shown) so as to be driven only during the rotation of the receiver shaft 60. The drive ratio, however, is preferably such that the reel 41 is "over driven", that is, it tends to turn more than two notches per swing of assembly A toward the operator. In this way if a package should be missing from its proper place due to a failure on the part of the operator, the reel will present the package from a second set of notches. When every available pair of notches is filled the belt simply slips as each package reaches assembly A and jams in the notches of the end seizers 14 to bring the feed reel to rest.

The band feeding mechanism shown in the drawings is adapted to feed the bands from a stack of the same contained in a reservoir 70 in which the bands gravitate and rest upon the inturned shelves 71 at the bottom of the reservoir. The reservoir is suitably held in a fixed but adjustable position. The top of the stack of bands is pressed upon by means of two weights 73 which bear upon the stack and force the stack downwardly and against the inturned shelves 71. One edge of the

stack of bands is supported by a perforating needle or pricker 74 adjustably held in a bracket 75 affixed to the reservoir. This pricker 74 by reason of the weight 73 overlying the pricker 74 and also the weight of the stack of bands in the reservoir perforates two or perhaps three of the lowermost bands in the stack. By this means the lowermost band can be pushed from the bottom of the stack so that it can be separated from the same by the pincers hereinafter described without displacing the adjacent overlying band. The separation of the lowermost band from the stack is accomplished by means of a pair of friction members or fingers 76, preferably made of rubber, the reciprocating motion of which displaces laterally the lowermost band by tearing it away from the impaling pricker. In the device as shown two rubber fingers 76 are affixed to an oscillating arm 77 pivoted at 78 and moved against the force of the spring 79 by means of the roller 80 camming against the under surface of the arm 77. This roller 80 is carried by the swinging arm 81 affixed to the rock shaft 82 and driven through a suitable arrangement of cam-actuated cranks and levers (not fully shown) in the manner hereinafter described. A given label, having been displaced from a position directly beneath the overlying stack or pile of bands by means of the rubbers or friction members 76, is grasped by means of the right and left pairs of label or band pincers, the upper ones 85 and the lower ones 86, mounted on the shaft 87 carried by the outer end of the swinging arm 81. The pincers 85 and 86 tend to approach one another under the influence of coil springs 86^a within the assembly. The upper pincers 85 are held in a fixed position with reference to the shaft 87 but the lower pincers 86 have the requisite scope of movement when suitably moved against the influence of the concealed springs before mentioned. Between the adjacent surfaces of the pincers 85 and 86 is a T-shaped member 88 adapted to be slid back and forth between the pincers and wedge them apart or permit them to approach one another as the wedge member is accordingly slid from one position to the other of its two principal positions. This wedge member is pivotally affixed to a rocking lever 89 which lever 89 is pivoted on the shaft 87 between the respective pairs of pincers. The lower portion of the lever 89 has two extensions 89^a and 89^c which are adapted to be actuated or cammed by the spring pressed members 90^b and 90^d pivotally mounted on their respective pins 91, which are affixed to the frame of the machine. These members 90^b and 90^d are spring pressed, as shown in Fig. 12, so that they tend to approach one another except for the stops 92 which limit their approaching movement at their respective positions as shown in Fig. 12.

Referring to Figs. 2, 3, 4, 5 and 6, which show successive positions in the movement of the band handling device, attention is first called to Fig. 2 which shows the pincers as they are returning to get a band to place in the assembly A. In Fig. 2 the pincers 85 and 86 are shown at the moment of their opening which is caused by means of the wedging of the T-shaped member 88 in between the adjacent surfaces of the pincers 85 and 86, so that the head of the T-shaped member passes from the notches, in the lower surfaces of the upper pincers 85 and slides along the adjacent tapered surfaces so as to 10 cam them apart. Motion is imparted to the T-shaped member 88 through the medium of the lever 89 and its extension 89^a which encounters the member 90^b on the first backward stroke in the cycle of movements of 15 the pincers. Passing from Fig. 2 to Fig. 3 the pincers are next shown in a wire-open position ready to advance to grip a band b which has been thrust from beneath the overlying pile of bands by means of the rubber fingers 76. This takes place as the pincers are swinging from the position shown in Fig. 2 to that shown in Fig. 3 where the pincers have reached their extreme backward movement. In Fig. 4 the pincers are shown 20 as having gripped an edge of the lowermost band which has been laterally displaced from beneath the stock by the rubber fingers 76. The pincers are caused to grip by means of the member 90^d which encounters the lever 25 extension 89^c, retarding the extension as the pincers move forwardly sufficient to cause the T-shaped wedge 88 to be slid forwardly into the notches of the upper pincers 85, thus permitting the springs to urge the lower pincers 30 36 up against the upper pincers 85 so to grip the band. Following the gripping of the lowermost band, as shown in Fig. 4, the pincers again move backwards to the position shown in Fig. 5 so as to pull the band 35 from the inturned shelves 71 by which means the band was supported after having been torn from the pricker 74. On the second forward stroke of the pincers the band is carried forwardly and down and along a 40 guide 93 which at its lower portion carries two cam members 94 which are adapted to cam open the lower pincers 86 by reason of their contact with the projections 86^b on each of the lower pincers 86. Thus, as the pincers 45 near the bottom of their second forward stroke the pincers release their grip upon the band b, permitting it to gravitate into the adjustable rest 92 preparatory to the band and package being gripped together by the 50 assembly A (see Fig. 6). In Fig. 6 the pincers are shown as about to release the band as just described. It will be evident from the description of the members 90^b and 90^d that they are laterally offset from one another so 55 that each contacts only with its own lever ex-

tension, that is, 89^a contacts only with 90^b, and 89^c contacts only with 90^d. Because 90^b and 90^d are spring pressed, they are free to move out of their position except when their respective lever extensions attempt to move them against the pins 92 which then resist and move their respective lever extensions and in turn cause the movement of the T-shaped wedge member 88, as above described. 70

It will be seen from the foregoing description and accompanying drawings that the entire mechanism is actuated and controlled by means of the various springs and cam movements, and timed from the cam shaft to which the driving cams are affixed, from 80 which description and drawings and mode of operation and advantages of my package banding machine will be clearly and sufficiently understood and appreciated by those skilled in the art. The embodiment of the 85 invention substantially as herein disclosed has been found to give very satisfactory service in every day factory use in the hands of unskilled operatives. 90

It will, of course, be understood that while I have illustrated one practical embodiment of my invention, I do not limit myself to the precise form construction and arrangement of its several parts, nor to, for example, the exact method of affixing together the overlapping portions of the flexible wrapper. I therefore am entitled to reserve and do reserve the privilege of adopting all such changes and modifications within the spirit and scope of the invention as claimed. 95

I claim:—

1. In a package wrapping machine, having means to receive a band and assemble it with a package, a reservoir holding a stack of bands, means adapted to resist the lateral displacement of at least two of the bands at one end of said stack, mechanical means adapted to laterally displace a band from said end of the stack, and means for taking the band thus displaced, and moving same in the direction of displacement to free the band from the stack, and then reversing the movement to carry said band to the receiving means. 105

2. In a package wrapping machine, having means to receive a band and assemble it with a package, a reservoir holding a stack of bands, a pricker adapted to perforate at least two of the bands at one end of said stack, mechanical means adapted to laterally displace a band from said end of the stack and means for taking the band thus displaced, and moving same in the direction of displacement to free the band from the stack, and then reversing the movement to carry said band to the receiving means. 115

3. In a package wrapping machine, having means to receive a band and assemble it with a package, a reservoir holding a stack of bands, means adapted to resist the lateral displacement of at least 120

125

two of the bands at one end of said stack, means adapted to move by friction and laterally displace a band from said end of the stack, and means for taking the band thus displaced, and moving same in the direction of displacement to free the band from the stack, and then reversing the movement to carry said band to the receiving means.

4. In a package wrapping machine, having means to receive a band and assemble it with a package, a reservoir holding a stack of bands, means adapted to resist the lateral displacement of at least two of the bands at one end of said stack, mechanical means adapted to laterally displace a band from said end of the stack while leaving the adjacent band held by the first mentioned means, and means for taking the band thus displaced, and moving same in the direction of displacement to free the band from the stack, and then reversing the movement to carry said band to the receiving means, said last means comprising gripping jaws, means slidable between said jaws to wedge same apart when in one position and to permit a gripping action when in another position.

5. In a package wrapping machine, having means to receive a band and assemble it with a package, a reservoir holding a stack of bands, a pricker adapted to perforate at least two of the bands at one end of said stack, mechanical means adapted to laterally displace a band from said end of the stack while leaving the adjacent band held by said pricker, and means for taking the band thus displaced, and moving same in the direction of displacement to free the band from the stack, and then reversing the movement to carry said band to the receiving means, said last means comprising gripping jaws, means slidable between said jaws to wedge same apart when in one position and to permit a gripping action when in another position.

6. In a package wrapping machine, having means to receive a band and assemble it with a package, a reservoir holding a stack of bands, means adapted to resist the lateral displacement of at least two of the bands at one end of said stack, means adapted to move by friction and laterally displace a band from said end of the stack while leaving the adjacent band held by the first mentioned means, and means for taking the band thus displaced, and moving same in the direction of displacement to free the band from the stack, and then reversing the movement to carry said band to the receiving means, said last means comprising gripping jaws, means slidable between said jaws to wedge same apart when in one position and to permit a gripping action when in another position.

7. In a package wrapping machine having means for receiving a band and assembling said band with a package in a holder adapted to grip the package and band together, a res-

ervoir holding a stack of bands, a device to separate mechanically a band from said stack by movement in one direction and including means to retain an adjacent band in said reservoir during said separation, said device being effective to reverse the movement of the band after separation thereby to place the band in the receiving means.

8. In a package wrapping machine, having means for receiving a band and assembling it with a package, a reservoir holding a stack of bands, a pricker adapted to perforate at least two of the bands at one end of said stack, laterally movable means adapted to frictionally engage and laterally displace a band from said end of the stack, while leaving the adjacent band held by said pricker, and a pair of jaws adapted to grip the band thus displaced and move it to said receiving means, and means slidable between said pair of jaws to wedge same apart when the jaws are in one position and to permit a gripping action thereof when in another position.

9. In a package wrapping machine, having means for receiving a band and assembling it with a package, a reservoir holding a stack of bands, a pricker adapted to perforate at least two of the bands at one end of said stack, laterally movable means adapted to frictionally engage and laterally displace a band from said end of the stack, while leaving the adjacent band held by said pricker, and a pair of jaws adapted to grip the band thus displaced and move it to said receiving means, and spring means to close the jaws to grip the band and cam means to subsequently wedge open said jaws to release the band.

10. In a package wrapping machine, having means for receiving a band and assembling it with a package, a reservoir holding a stack of bands, a pricker adapted to perforate at least two of the bands at one end of said stack, laterally movable means adapted to frictionally engage and laterally displace a band from said end of the stack while leaving the adjacent band held by said pricker, and a pair of jaws adapted to grip the band thus displaced, said jaws having a range of movement from the stack to the receiving means, and wedging means slidable between the jaws to open same when in one position and to permit a closing of said jaws to grip the band and to open said jaws at the receiving means to release the band.

ANALDO M. ENGLISH.
